UNITED STATES PATENT OFFICE.

DANTE CAVICCHIOLI, OF NEW YORK, N. Y.

TOY AND GAME DEVICE.

Application filed February 7, 1923. Serial No. 617,452.

To all whom it may concern:

Be it known that I, DANTE CAVICCHIOLI, a citizen of the United States, and residing at New York city, in the county of New York and State of New York, have invented certain new and useful Improvements in Toy and Game Devices, of which the following is a specification, such as will enable those skilled in the art to which it appertains to 10 make and use the same.

This invention relates to toy or game devices and particularly to devices of this class comprising a board member having a plurality of apertures, said board member being fashioned to represent a predetermined subject, and the board member being provided with pivotally suspended bodies positioned in the apertures thereof, whereby spherical members, rings or the like may be advanced 20 to the board to pass through the apertures of the board, in which the bodies are suspended and said bodies being designed to represent predetermined characters, and the object of the invention is to provide a toy or 25 game device of the class and for the purpose specified, which is designed to amuse both young and old, and which is simple in construction, efficient in use and constructed as hereinafter described and claimed.

The invention is fully disclosed in the following specification of which the accompanying drawing forms a part, in which the separate parts of my improvement are designated by suitable reference characters in 35 each of the views, and in which:—

Fig. 1 is a front view of my improved device in an operative position.

Fig. 2 is a back view of the device shown in Fig. 1 with part of the construction 40 broken away.

Fig. 3 is a section on the line 3—3 of Fig. 1 and on an enlarged scale.

Fig. 4 is a detail view of a modified form of construction which I may employ; and,

Fig. 5 is a partial section on the line 5—5 of Fig. 4.

In practice I provide a board member 10 which in the construction shown is oblong and rectangular in form and may be composed of cardboard or any other material, and in Fig. 1 of the drawing, the front face of the board member is fashioned or designed to represent a castle or the entrance to a castle, and the bottom edge of the board 55 member 10 is cut out as shown at 11 to form

an elongated aperture and cut out as shown at 12 to form other apertures or openings, which register with the aperture 11, and the apertures 12 are designed to represent the door openings or gates controlling the admission to the castle as will be apparent. Mounted upon the back of the board member 10 adjacent to the top thereof is an elongated strip 13 which serves to retain a plurality of wire loop members 14 in connection with the board member 10, said loop members being substantially U-shaped in form and extending downwardly into and registering with the apertures 12 in the board member as clearly shown in Figs. 1 60 and 2 of the drawing, and rotatably mounted on the crosshead portions of the loop members 14 are figured bodies 15 which in the construction shown are ornamented to represent a king, queen and jack, said bodies 70 being located in the separate apertures 12 of the board member.

At the ends of the strip 13 are backwardly directed ears 16 in which is pivotally mounted a U-shaped frame member 17 which constitutes an easel back or support for the board member, as clearly shown in Fig. 3 of the drawing, and slidably mounted on the frame member 17 is a longitudinal plate 18, which in the operative position of the toy 80 device is normally located at the base of the frame 17, and serves as a stop or backing for ball or other members used in playing the game. One side of the frame member 17 is provided with an extension 19 adapted to engage a keeper 20 on one end by a pivoted lever 21 for locking the frame 17 in its operative position, and the other end 23 of said lever is adapted to engage the frame 17 when in its collapsed position for holding 90 said frame in engagement with the board member. Another pivoted member 23 is provided for engaging the plate 18 as indicated in dotted lines in Fig. 2, when the entire game device is collapsed and boxed for shipment or other purposes.

In Figs. 1 to 3 inclusive the plate member 18 is preferably composed of sheet metal, while in Figs. 4 and 5 of the drawing, I have shown a plate member 24 composed of cardboard or similar material mounted upon the side members of the frame 17 by U-shaped metallic clips 25, but this backing member will serve the same purpose as the backing member 18.

In the use of my improved toy or game device, it will be understood that the device is mounted upon a floor or other surface in the manner shown in Figs. 1 and 3 of the drawing, in which position of the device the figured bodies 15 are suspended in the apertures 12, and balls or other bodies are advanced by hand or by the use of a suitable shooter, pistol or the like to strike 10 the figured bodies 15 and suspend the same on their supports, and thus gain admittance to the castle through the door or gate openings. This game will require skill on the part of the player, and by designating the 15 separate figures 15 to give predetermined value thereto, a game of points, honors, or the like may be played, and if desired and by using a greater number of apertures 12 and figured bodies 15, a card game or other 20 game well-known or otherwise may be played, and various changes in and modifications of the construction herein shown and described may be made within the scope of the appended claims without departing 25 from the spirit of my invention or sacrificing its advantages.

Having fully described my invention, what I claim as new and desire to secure by Letters Patent, is:—

30 1. A device of the class described comprising a body provided with a plurality of longitudinally spaced apertures, characterized figures movably suspended in said apertures, means for supporting said body, a 35 backing member mounted in connection with said supporting means and adjustable thereon, and means for locking said supporting means in its operative position.

2. A device of the class described comprising a body provided with a plurality of longitudinally spaced apertures, characterized figures movably suspended in said apertures, means for supporting said body, a backing member mounted in connection 45 with said supporting means and adjustable thereon, means for locking said supporting means in its operative position, the separate parts of the device being collapsible and 50 means for retaining the parts in a collapsed position.

3. A game device of the class described comprising a characterized game board having spaced apertures, a plurality of characterized bodies suspended in said apertures 55 and capable of rotation on their supports, a supporting frame movably mounted in connection with said body and adapted to support the same in a predetermined position, means for retaining said supporting 60 frame in its operative position, and said

supporting frame being provided with a backing member.

4. A game device of the class described comprising a characterized game board having spaced apertures, a plurality of characterized bodies suspended in said apertures and capable of rotation on their supports, a supporting frame movably mounted in connection with said body and adapted to support the same in a predetermined position, means for retaining said supporting frame in its operative position, said supporting frame being provided with a backing member, the separate parts of the game device being collapsible, and means for retaining 70 said parts in a collapsed position.

5. A game device of the class described comprising a board member provided at its lower edge with an elongated aperture having a plurality of other apertures registering therewith, a plurality of supporting members mounted in connection with the back of said board member and registering with said last named apertures, and characterized bodies rotatably mounted on said 80 supporting members.

6. A game device of the class described comprising a board member provided at its lower edge with an elongated aperture having a plurality of other apertures registering therewith, a plurality of supporting members mounted in connection with the back of said board member and registering with said last named apertures, characterized bodies rotatably mounted on said 90 supporting members, a yoke-shaped frame pivotally mounted in connection with the back of said board member, by means of which said board member may be supported in an inclined position, said yoke-shaped frame 95 being provided with a backing member, and means for retaining said frame in its operative position.

7. A game device of the class described comprising a board member provided at its lower edge with an elongated aperture having a plurality of other apertures registering therewith, a transverse strip mounted at the back of the board member, a plurality of supporting members mounted in connection with said strip and registering with said last named apertures, characterized bodies rotatably mounted on said supporting members, and a yoke-shaped supporting frame pivotally mounted in connection with 100 the end portions of said strip.

In testimony that I claim the foregoing as my invention I have signed my name this 5th day of Feb., 1923.

DANTE CAVICCHIOLI.
